UNITED STATES PATENT OFFICE.

GEORGE McCORD, OF NEW YORK, N. Y.

HOT-AIR FURNACE.

SPECIFICATION forming part of Letters Patent No. 242,549, dated June 7, 1881.

Application filed February 24, 1881. (No model.)

To all whom it may concern:

Be it known that I, GEORGE McCORD, of the city, county, and State of New York, have invented new and useful Improvements in Hot-Air Furnaces, of which the following is a specification.

This invention has for its object the saving of heat usually lost by radiation, and at the same time keeping the cellar at a proper degree of temperature, so that vegetables of various kinds will not be spoiled by the usual high degree of temperature caused by furnaces in such places; and the invention consists in furnishing a non-radiating covering to the furnace proper, so that an air-space is provided between the furnace and the ordinary brick inclosure, and of such a character that the said covering will prevent the heat from radiating to the brick walls outside of the furnace, and in combining a cold-air conduit and a valve with the said outer casing and the brick inclosure, so that a certain degree of temperature may be maintained at all times in the said cellar or basement as will hereinafter appear.

In the drawings, Figure 1 represents a plan of the entire apparatus. Fig. 2 is a vertical section of the same.

At A is shown the furnace proper, with a coal-chute at B and a smoke-pipe at C.

Ordinarily such furnaces are inclosed in a chamber made of brick, as represented at D, and from said chamber the pipes lead to the different rooms or places to be heated, and the consequence of such a construction is that the walls of said chamber soon become so heated that the cellar is practically worthless as a store-room for green fruits and vegetables, &c. To remedy this difficulty I surround the furnace proper, or the heater, with a shield or cov-

ering, preferably of sheet metal, as represented at E, and of sufficient size to nearly fill the brick chamber, thereby leaving a narrow space between the said shield and the inner faces of the walls of the brick-work. Said shield is

made in sections, as represented in the plan, and the edges of the sections may be formed, as represented, by a tongue-and-groove joint and fastened by screws, as at F, so that the parts may be removed when repairs are required for the furnace. The cover of said

shield is also made loose and formed with a flange, as at G, to fit down over the top of the lining, like a lid on a metal can, and from this cover the hot-air-pipe connections are made in the ordinary manner. Near or toward the center of said cover, on its under side, are fastened deflecting-plates, as shown at H, to throw the heat rising from the furnace toward the hot-air pipes.

To properly control the temperature in the space between the brick walls and the said shield or casing a small perforated air-pipe, K, is connected with the pipe that supplies the furnace-chamber with cold air, as at L, and a valve, as at M, to regulate the supply of cold air to the said perforated pipe, and which is laid in the bottom of the space, between the shield and the brick-work, and then it extends up in one corner and to a point outside of the brick chamber, where it has an outlet in the cellar. By such an arrangement it will be seen that a small quantity of cold air may be evenly distributed in the said space, and when allowed to escape may thereby keep the temperature in the cellar at a properly regulated degree of heat, and whenever it is warm enough the supply of air to the perforated pipe may be stopped by the valve.

An opening, as at N, may be formed in one side of the shield or casing, as indicated by the dotted lines, so that a person may enter the casing to repair the furnace, and this may be provided with a shutter similar to the one for closing the entrance to the brick chamber, as shown at O in the drawings. Said shield or casing will be found to be most useful when made of sheet-tin or galvanized sheet-iron, though it may be formed of cast-metal plates and fitted in sections, as represented.

It is evident that instead of the outer casing of brick-work a metal casing may be used, as is often the case. In such arrangement the shield or casing must be inserted between them to form the cold-air space.

Having thus fully described my invention, I desire to claim—

In a hot-air furnace constructed with a shield or casing between the furnace proper and the outer chamber to form an outer air-space, as described, a perforated pipe placed

in the lower portion of said outer air-space, | provided with a regulating-valve, and com-
municating with the external atmosphere,
whereby the air-space is at all times kept cool,
5 and the heating of the brick or other inclosing-
chamber is prevented.

In testimony whereof I have hereunto set

my hand in the presence of two subscribing
witnesses.

GEORGE McCORD.
